UNITED STATES PATENT OFFICE.

ALFRED H. HUMPHREY, OF NEW YORK, N. Y.

DESIGN FOR A FIREBACK FOR GAS-STOVES.

57,129.

Specification for Design.

Patented Feb. 22, 1921.

Application filed May 3, 1920. Serial No. 378,696. Term of patent 14 years.

To all whom it may concern:

Be it known that I, ALFRED H. HUMPHREY, a citizen of the United States, and resident of the city of New York, county of New York, and State New York, U. S. A., (whose post-office address is 44 West Broadway, New York city, New York), have invented a new, original, and ornamental Design for a Fireback for Gas-Stoves, of which the following is a specification, reference being had to the accompanying draw-

ing, forming a part thereof, which is a front perspective of a gas stove showing my new design.

I claim:

The ornamental design for a fireback for gas stoves as shown.

ALFRED H. HUMPHREY.
